Attorneys.

UNITED STATES PATENT OFFICE.

ARTHUR H. BARTELT, OF MILWAUKEE, WISCONSIN.

WRENCH.

1,261,006.

Specification of Letters Patent.

Patented Apr. 2, 1918.

Application filed August 13, 1917. Serial No. 185,914.

To all whom it may concern:

Be it known that I, ARTHUR H. BARTELT, a citizen of the United States, and resident of Milwaukee, in the county of Milwaukee, 5 and State of Wisconsin, have invented new and useful Improvements in Wrenches, of which the following is a description, reference being had to the accompanying drawings, which are a part of this specification.

10 The invention relates to wrenches and more particularly to a wrench for use in making the adjustment of an ordinary form of tappet valve.

The ordinary form of tappet valve which 15 is frequently used in automobile engines consists of the valve and a cam operated tappet device consisting of a main body portion and an adjusting screw which is secured in adjusted position with respect to 20 the main portion by a lock nut. In making the adjustment of this type of valve it is necessary to loosen the lock nut and then turn the adjusting screw to proper position and hold both it and the main body portion 25 of the tappet device against movement while the lock nut is being tightened up. Formerly it has been necessary to employ two operators to accomplish the adjustment, because of the two parts to be held and the 30 lock nut to be moved and to obviate this difficulty I have provided a wrench whereby the adjustment of the valve may be accomplished easily and quickly by one man as the wrench held in one hand, holds the main 35 body of the tappet device and the adjusting screw in adjusted position while the operator tightens up on the lock nut with a wrench held in the other hand.

The invention further consists in the several features hereinafter set forth.

In the drawings:

Figure 1 is a perspective view of the device embodying the invention together with a view of the valve, parts being broken away 45 and parts being shown in section;

Fig. 2 is a side view of the device, parts being shown in section;

Fig. 3 is a plan view of the device embodying the invention.

50 In Figs. 1 and 2 I have illustrated a common form of tappet valve in connection with which my wrench is to be used for adjusting the valve. This consists of a valve member having a head 4 and stem 5, a bearing sleeve 6, a tappet member 7 slidably and 55 rotatably mounted in said sleeve and carry-

ing a round flat head 8 which contacts with a cam 9 on the valve shaft 10, an adjusting screw 11 having threaded engagement with the upper end of the member 7 and a nut 60 12 for locking the screw in adjusted position, the upper end of the member 7 also having flat faces 13 for receiving a wrench to hold said member 7 against turning movement when the valve is being adjusted. Tappet valves of this kind are set so that there will be a slight clearance between the end 65 of the stem 5 and the head of the screw 11 when the lowest portion of the cam 9 is in contact with the head 8. Heretofore, it has 70 been necessary for two persons to make the adjustment each person having a wrench, one to engage the flat faces 13 of the member 7 and the other to engage the head of the screw 11 and then one of the persons uses 75 another wrench to turn the lock nut 12 to secure the parts in adjusted position. With the present device one person with one hand holds both the adjusting screw 11 and the member 7 while with the other hand he may 80 tighten the nut 12 by a wrench 15, shown in dotted lines in Fig. 2.

My device consists of a main handle 16 and wrenches 17 and 18 spaced apart from each other and adjustably secured to the 85 handle 16. The wrench 17 is for engaging the flat faces 13 to hold the member 7 and is secured to the handle 16 so that it may be spaced at different distances from the wrench 18, which holds the screw 11, by 90 means of screw bolts 19 which pass through threaded apertures 20 in the handle through apertures 20' in the wrench 17 and carry clamping nuts 21 and 22 for holding the wrench 17 clamped between them. While 95 for any given make of valve it will be understood that this adjustable connection might not be necessary however to permit the tool to be used on different makes of valve it is necessary to vary the distance between the wrenches 17 and 18 as the distance between the top of the tappet member 7 and the adjusting screw 11 varies.

The wrench 18 is for engaging the head of the screw 11 and since the faces of the 105 polygonal head of the screw will not always lie in the same place with the faces 13 on the member 7 and since the relative sizes of these surfaces to be engaged differ it is necessary to provide an adjustable connection between this wrench and wrench 17. 110 This adjustable connection is formed by a

bolt 23 having a squared portion 24 slidably mounted in a transverse slot 25 in the handle 16, an adjustable clamping member or nut 26 mounted on the bolt, the shank 27 of the wrench having a longitudinally extending slot 28 therein for receiving the bolt 23, the wrench being held at different positions of angular adjustment and different distances with respect to the handle 16 10 by moving the bolt 23 in the slot 25 and the wrench 18 with respect to said bolt and securing it in adjusted position between the handle and the nut 26. The slot 28 is open so that the wrench may be easily removed 15 and turned over to increase the radius of turning of the wrench.

With this construction the operator adjusts the wrenches 17 and 18 at the proper distance with respect to each other to fit the 20 particular make of valve so that the wrench 17 will lie in the plane of the faces 13 on the member 7 when the wrench 18 lies in the plane of the head of the screw 11. For a given make of valve this adjustment need 25 only be made once and of course the wrench 17 and handle 16 might be made integral to space the wrench 18 at a fixed distance from the wrench 17 for any given make of valve. The wrench 18 is then adjusted so as to 30 properly engage the head of the screw 11 by loosening up the nut 26 and moving the wrench with respect to the bolt 23 and the bolt 23 with respect to the handle 16 and then tightening up on the bolt 23. The tool 35 is then brought up so that the wrench 17 engages the faces 13 of the member 7 and wrench 18 the head of the screw 11 and said parts being held by the wrench in one hand, the operator uses his other hand to loosen 40 the lock nut 12 as by using a wrench 15. When the nut 12 is loosened, the operator adjusts the position of the head of the screw 11 with respect to the end of the valve stem 5 so as to provide a slight clearance there- 45 between when the valve is closed. This adjustment for clearance having been accomplished the parts 11 and 7 are held against movement by the operator with one hand through the use of my wrench, while with 50 the other hand the operator manipulates the

wrench 15 to tighten the nut 12 to secure the parts 11 and 7 in adjusted position.

The invention thus exemplifies a simple and efficient form of tool well adapted for the purposes desired.

What I claim as my invention is:

1. In a device of the character described, the combination of a pair of wrenches fixedly secured together in sidewise spaced relation, one of said wrenches being angularly adjustable with respect to the other for simultaneous use of both wrenches.

2. In a device of the character described, the combination of a pair of wrenches adjustably fixedly secured together in sidewise spaced relation, one of said wrenches being angularly adjustable with respect to the other for simultaneous use of both wrenches.

3. In a device of the character described, the combination of a handle, a pair of sidewise spaced apart wrenches fixedly secured thereto, one of said wrenches being adjustable lengthwise and angularly with respect to said handle.

4. In a device of the character described, the combination of a handle having a transverse slot therein, a wrench having a lengthwise slot therein, a clamping member passing through said slots to secure said wrench to said handle, a second wrench, and means for adjustably securing said second wrench to the handle in spaced relation to the first wrench.

5. In a device of the character described, the combination of a pair of wrenches, means rigidly connected to one of said wrenches and adjustably secured to the other wrench for holding said wrenches in adjustable sidewise spaced relation with respect to each other.

6. In a device of the character described the combination of a member, a wrench secured thereto for lengthwise and angular adjustment with respect thereto, a second wrench, and means for adjustably fixedly securing said second wrench to said member in sidewise spaced relation to the first wrench.

In testimony whereof, I affix my signature.

ARTHUR H. BARTELT.
